Company, Chicago, Ill., a corporation of Dela-
ware

Application November 12, 1937, Serial No. 174,167

10 Claims. (Cl. 246—163)

This invention relates to certain new and useful improvements in a portable derailler adapted to be secured to a railroad rail to effect derailment of cars or other rolling stock.

5 Devices of the above character are used as safety measures in many situations, for example, to prevent cars from being moved onto a section of track where workmen are engaged in repairing cars thereon or where a section of track is temporarily closed for any reason.

An object of the present invention is to provide clamping means of simplified construction for removably securing a derailler block to a railroad rail, the clamping means being readily adjustable whereby the derailler block may be readily and conveniently clamped to rails of various sizes. Other objects and advantages will be readily apparent from the detailed description of one embodiment of the invention shown in the accompanying drawings wherein:

Fig. 1 is a plan view of a derailler block secured to a railroad rail in accordance with this invention.

Fig. 2 is a side view of the derailler block and the clamping elements connected therewith.

Fig. 3 is an end view of the derailler block illustrating partly in section, the clamping positions of the several clamping elements.

Fig. 4 is a view similar to Fig. 3 but illustrating the clamping elements released from the rail to permit the derailler block to be removed therefrom, and

Fig. 5 is a sectional view taken on line 5—5 of Fig. 3.

Referring to the drawings, 10 designates a railroad rail and 11 a derailler block mounted on the head portion of the rail in a position to elevate a car wheel and direct the flange of said wheel across the top of the rail. The block may be of any suitable construction having a base portion 12 adapted to seat on the top surface of a rail head and having a wheel flange receiving groove 13. The base portion of the block is provided with a forwardly tapered extension 14 which seats on top of the rail head in advance of the grooved portion of the block so that the tread portion of a wheel will run upon the extension 14 and thereby elevate the wheel relative to the top of the rail. The flange of the wheel enters the groove 13 and is directed by the curved walls of the groove across the top of the rail. The derailler block is preferably formed at one side with a depending angular flange 15 adapted to engage the outer side face of the rail head and project beneath the under surface of the head. A pair

of ears 16—16 and a lug 17 depend from the bottom of the block at the other side of the rail. These members are sufficiently spaced from the flange 15 to permit the derailler block to be applied to rail heads of different sizes.

The derailler block is removably clamped to the rail by means of mechanism comprising a clamping lever 18, a clamp bolt 19, and an adjustable screw member 20. The lever 18 is pivoted between the ears 16—16 by means of a pivot bolt 21 so as to normally hang downwardly into engagement with the edge of the rail base. Preferably, the inner face of the lever, near the pivotal axis thereof, is formed with a projection 23 adapted to extend beneath the under surface 24 of the rail head when the lever is in its lowermost position. The said projection 23 and the inturned end of the angular flange 15 cooperate to lock the derailler block on the rail when the lever is held in its lower position. Preferably the inner face of the lever is curved, as indicated at 25, and the lower end is provided with an elongated opening 26 to receive the threaded end of a clamp bolt 27. The other end of the bolt is provided with a hook 28 for engaging over the edge of the base flange 29 of the rail. The lever is held clamped to the base flange 22 of the rail by means of a winged nut 30 threaded on the bolt 27 so as to engage the outer face of the lever 18.

When the lever 18 is clamped to the rail in the manner above described, the projection 23 of the lever and the angular flange 15 provide a suitable lock for rails of certain sizes, the elongated opening 26 of the lever providing for vertical adjustments to accommodate rails of different heights. In most situations, however, it is desirable to maintain the angular flange 15 firmly clamped against the outer face of the rail head. This clamping engagement is obtained in the present invention by means of the screw member 20 which extends through the lever 18 and may be suitably adjusted to bear against the web of the rail adjacent the rail head. Preferably, the screw 20 extends loosely through the lever 18, but has a threaded engagement with a nut 31 which is non-rotatably fitted in a recess 32 in the lever. The outer end of the screw member 20 is provided with a sliding pin 33 which serves as a lever for operating the screw member 20.

The lever 18 is preferably provided at its upper end with a portion 34 formed with a slot 35 to receive the lower end of a signal staff 36. Any suitable flag or other signal may be attached to the upper end of the staff 36 to indicate that the

section of track, to which the derail block is applied, is closed.

In order to prevent unauthorized removal of the derail block, an ordinary padlock 31 may be applied by inserting the lock bolt through an aperture 38 formed in one of the ears 16 so as to prevent upward swinging of the lever 18.

When it is desired to remove the derail block from the rail, the wing nut 30 is loosened to permit the clamp bolt 21 to be disengaged from the base flange 29. The lever 18 can be then swung outwardly and upwardly, as shown in Fig. 4 of the drawings, until the inner end of the screw member 20 clears the lower edge of the rail head, whereby the derail block may be removed by a turning movement in the direction indicated by the arrow in Fig. 4 of the drawings. It will be apparent from the above description, that the derail block can be removed and re-applied to the rail without altering the adjustment of the screw member 20.

While the invention is illustrated in connection with one approved form, it will be understood that the scope of the invention is not restricted to the specific constructions shown and described except insofar as specific limitations appear in the appended claims.

We claim:

1. In combination with a portable derail block adapted to be positioned on the head of a rail and having a depending angular abutment for embracing one side face and the adjacent under surface of a rail head at one side of the rail; means for removably clamping the block to the rail comprising an arm pivotally attached to the block and depending therefrom at the other side of the rail, an adjustable screw member extending through the arm and adapted, upon movement of the arm toward the rail, to bear against the rail at a location beneath the head to clamp the derail block on the rail, and means engaging the said arm and engaging the rail flange on the first mentioned side of the rail for holding the arm and said adjustable screw clamped against the rail.
2. In combination with a portable derail block adapted to be positioned on the head of a rail and having a depending angular abutment for embracing one side face and the adjacent under surface of a rail head at one side of the rail; means for removably clamping the block to the rail comprising an arm pivotally attached to the block and depending therefrom at the other side of the rail, an adjustable screw member extending through the arm and adapted, upon movement of the arm toward the rail, to bear against the rail at a location beneath the head thereof to clamp the derail block on the rail, and means for holding the arm and said adjustable screw member clamped against the rail comprising a bolt engaging the lower portion of said arm and having a hooked end for engaging the rail base flange on the first mentioned side of the rail; there being a nut threaded on the bolt and engaging the arm to force the arm toward the rail.
3. In combination with a portable derail block adapted to be positioned on the head of a rail and having a depending angular abutment for embracing one side face and the adjacent under surface of a rail head at one side of the rail; means for removably clamping the block to the rail comprising an arm pivotally attached to the block and depending therefrom at the other side of the rail, an adjustable screw member extending through the arm and adapted, upon move-

ment of the arm toward the rail, to bear against the rail at a location beneath the head thereof to clamp the derail block on the rail, and means for holding the arm and said adjustable screw member clamped against the rail comprising a bolt extending through an opening in the lower portion of said arm and having a hooked end for engaging the rail base flange on the first mentioned side of the rail; the bolt receiving opening in the arm being elongated to facilitate application of the device to rails of different heights and there being a nut threaded on the bolt and engaging the arm to force the arm toward the rail.

4. In combination with a portable derail block adapted to be positioned on the head of a rail and having a depending angular abutment along one side for embracing one side and the adjacent under surface of a rail head; of means for removably clamping the block to the rail comprising an arm pivotally attached to the block, and having a curved inner face adapted to bear against an edge portion of a rail base flange, an adjustable screw member extending through the upper portion of the arm and adapted, upon movement of the arm toward the rail, to extend beneath the rail head and bear against the vertical web of the rail to clamp the derail block on the rail, and means for releasably holding the said arm and screw member clamped against the rail, whereby the derail block may be quickly removed from the rail and reapplied thereto without disturbing the adjustment of said screw member.

5. In combination with a portable derail block adapted to be positioned on the head of a rail and having a depending angular abutment for embracing one side face and the adjacent under surface of a rail head at one side of the rail; of means for removably clamping the block to the rail comprising an arm pivotally attached to the block and depending therefrom at the other side of the rail and having a curved inner face adapted to bear against an edge portion of a rail base flange, an adjustable screw extending through the upper portion of the arm and adapted, upon movement of the arm toward the rail, to extend beneath the rail head and bear against the vertical web of the rail to clamp the derail block on the rail, and means for releasably holding the said arm and screw member clamped against the rail, comprising a hook bolt extending across beneath the rail base for engagement with the rail base flange on the first mentioned side of the rail and having a threaded end portion extending through the said arm; the bolt receiving end of the arm being elongated to facilitate application of the device to rails of various sizes and there being a nut threaded on the bolt to force the pivoted arm toward the rail.

6. In combination with a portable derail block adapted to be positioned on the head of a rail and having a depending angular abutment along one side for embracing one side and the adjacent under surface of a rail head; of means for removably clamping the block to the rail comprising a lever pivotally attached to the block to normally hang downwardly into engagement with one flange of the rail and provided with a projecting portion which extends beneath the rail head to prevent removal of the block when the lever is in its down position, and a clamp device for releasably clamping the lever in its down position.

7. In combination with a portable derail block adapted to be positioned on the head of a rail
